UNITED STATES PATENT OFFICE.

JOHN EDWARD NEALY, OF NEW YORK, N. Y.

VENDING-MACHINE.

1,250,487.

Specification of Letters Patent. Patented Dec. 18, 1917.

Application filed January 21, 1916. Serial No. 73,398.

To all whom it may concern:

Be it known that JOHN EDWARD NEALY, a citizen of the United States of America, residing at New York, in the county of New York and State of New York, has invented certain new and useful Improvements in Vending-Machines, of which the following is a specification.

This invention relates to coin-controlled tables and it has for its object the provision of a structure adapted to be supported upon a car wall between two adjacent facing seats and comprising a casing having means mounted therein normally tending to draw into said casing a flexible table such as canvas or other like material, said table being provided with means for attaching it to the arms of said seats when it is withdrawn from the casing, to support the table in such position that persons seated in the seats may use the table for playing cards or like games.

In many localities adjacent large cities the practice has sprung up among commuters who ride upon trains coming into and going out of said cities, to play cards to relieve the monotony of the ride to and from their work. It is a particular object of the present invention to provide means located between the seats of a car and upon the wall of a car so constructed that when a coin is deposited, a table and a pack of cards may be withdrawn and the table supported in such position that it may be used by the card players.

Further objects and advantages of the invention will be set forth in the detailed description which now follows.

In the accompanying drawings,

Figure 1 is a plan view of two adjacent seats of a railway car showing a part of the car body in section;

Fig. 2 is a vertical section between said seats and at one side of the table;

Fig. 3 is a detail view of a coin chute hereinafter described;

Fig. 4 is a vertical sectional view through the casing in which the table is contained, said section being taken upon line 4-4 of Fig. 1;

Fig. 5 is a vertical sectional view through said casing with certain of the parts shown in elevation and with the table in its retracted position;

Fig. 6 is a perspective view of a counter and an oscillatory shaft from which it is actuated;

Fig. 7 is an inner face view of the front wall of the casing, viewed in plan;

Fig. 8 is a detail sectional view illustrating the restraining hooks or fingers of the table;

Fig. 9 is a perspective view illustrating the means for oscillating the shaft from the coin-actuated mechanism;

Fig. 10 is a detail view of a manually operable finger which thrusts against the coin;

Fig. 11 is a perspective view of the operating handle;

Fig. 12 is a perspective view of the front plate of the casing and the parts carried thereby, said front plate being turned end for end from the position illustrated in Fig. 7;

Fig. 13 is a vertical sectional view through the front plate of the casing, showing the coin chute;

Fig. 14 is a horizontal sectional view of a portion of the front wall of the casing looking toward the operating handle, and

Fig. 15 is a fragmental side view showing associated therewith a spring for actuating the roller upon which the flexible table is wound.

Like numerals designate corresponding parts in all of the figures of the drawings.

In the drawings, 5 and 6 designate facing railway car seats and 7 and 8 designate the arms of said seats adjacent the aisle 9. Railway cars are usually provided with double walls indicated at 10 and 11 and with vertical ribs 12. In carrying out the invention, I mount within the wall of the car a casing 13. This casing comprises a rear wall 14, a top wall 15, a bottom wall 16 and end walls 17. The front of the casing consists of a removable plate 18 and for securing this plate in position clips 19 are secured at the opposite extremities of the plate 18, these clips being adapted to engage pins 20 carried by the end walls 17 of the casing. After these clips are thus engaged with the pins and the lower edge of the plate 18 has been forced inwardly until it abuts against the outer end of an angular plate 21, a bolt 22

of a key-controlled lock 23 is shot outwardly to engage behind the upturned portion 24 of said angular plate 21. The usual barrel into which the key is inserted for actuating the bolt 22 is indicated at 25. Mounted within the casing 13 is a roller 26 upon which a flexible table 27 made of canvas or

any other suitable material, is wound. A spring 28 has one of its ends attached to the shaft of the roller, as at 29 and the opposite end of the spring engages the end wall 17 of the casing, as indicated at 30, (see Fig. 15). This spring normally tends to wind the table onto the roller and to draw a strip 31 to which the outer edge of the table is secured against the outer wall 18 of the casing. Handles 32 are secured to this strip and provide means for drawing the table outwardly against the action of the roller 26. Rings 33 are secured to the strip 31 and these rings are adapted to engage hooks 34 secured beneath the overhanging portions of the arms 7 and 8 whereby the table is held in its operative position. Projecting downwardly from and carried by the strip 31 is a card receptacle 35 adapted to receive a deck of cards. This receptacle is cut away at 36 so that the cards may readily be projected from the top of the casing to be grasped and withdrawn therefrom. When the table is in its retracted position, the receptacle 35 fits within a shell 37 fixedly mounted within and forming a part of the casing 13. A coin-controlled mechanism is provided for preventing the withdrawal of the table and the cards from the casing 13 until a coin of the proper denomination has been deposited. This mechanism comprises a coin chute 38 having a horizontal portion 39 which opens through the front plate 18 of the casing, an inclined portion 40 and a vertical portion 41. A coin deposited in this coin chute is caused to assume a vertical position in the portion 41, where it overlies the end 42 of a lever 43. This lever is pivoted at 44 upon a stud 45. A spring 46 wound upon this stud has one of its ends engaged about a bearing stud 47 carried by the plate 18 and its opposite end in engagement with the lever 43, as at 48, this spring acting to maintain the end 49 of the lever in contact with a stop pin 50 carried by the plate 18. A shaft 51 is journaled in the stud 47 and is provided at its outer end with an operating handle 52. The inner end of the shaft 51 is angularly formed at 53 to engage in a correspondingly-shaped opening 54 of a finger 55. This finger is provided with an angular end 56 and it operates in a slot 57 formed in the wall of the coin chute and acts to engage the upper edge of the coin to thrust the lower edge of the coin against the end 42 of the lever 43, to thereby move said lever in the direction indicated by the arrows. The movement of the finger 55 is against the tension of a spring 58, one end of this spring being secured to the finger 55 and the opposite end of the spring being secured to a screw 59 threaded into a bracket 60, said screw serving to adjust the tension of the spring and the spring serving to nor-

mally maintain the finger 55 at the upper limit of its travel. Journaled in the bracket 60 and in brackets 61 and 62 is an oscillatory shaft 63. An arm 64 projects from this shaft and is pivoted at 65 to a link 66. The opposite end of this link is reduced and passes through a bifurcated swivel 67 carried by the lever 43. Consequently, when the lever 43 is rocked upon its pivot, it draws upon the link 66 and through the arm 64 oscillates shaft 63. The shaft 63 carries retaining hooks or fingers 68, the hook-like terminals 69 of which are adapted to engage in openings 70 formed in the strip 31. It will be apparent that with these hooks engaged in the openings 70, the withdrawal of the table will be prevented and with these hooks moved to the dotted line position illustrated in Fig. 8, the table may be withdrawn against the tension of the spring-actuated rollers 26. For binding the reduced portion of the link 66 to the bifurcated swivel 67, a screw 67^a (see, Fig. 9) is provided. An arm 71 rigid with the shaft 63 has one of the arms 74 of an L-shaped lever journaled in its outer end at 75. The other arm 76 of this lever passes through a slotted shaft 77 of a counter 78 so that when the shaft 63 is oscillated, a partial rotation will be imparted to shaft 77 and the counter will be advanced one number, in the usual manner of devices of this character.

A sight opening 79 covered by a glass 80 renders it possible for the person desiring to play cards to see whether there are any cards within the receptacle 35 before the coin is deposited. The provision of the shell 37 permits the withdrawal of the card receptacle 35, while preventing the entry of a person's hand to the interior of the casing 13, whereby the unauthorized removal of the coins deposited within the casing is prevented.

While the elements shown and described are well adapted to serve the purposes for which they are intended, it is to be understood that the invention is not limited to the precise construction set forth but that it includes within its purview such changes as may be made within the scope of the appended claims.

Having described my invention, what I claim is:

1. The combination with a containing casing and oppositely facing seating means, of a flexible table forming member carrying a playing card-receptacle, means for coiling said table forming member within said casing, and means applied to said table forming member, to provide for the uncoiling thereof in a direction at right-angles to that in which said seating means face, and means for the retention of said table in its uncoiled position.

2. The combination, with a containing casing and oppositely facing seating means, of a flexible table forming member carrying a playing-card receptacle resilient coiling means for said table-forming member within said casing, means applied to said table-forming member to provide for the uncoiling of the table-forming member in a direction at right angles to that in which said 10 seating means face, and interengaging means carried by the seat-arms and the outer edge of the table, adapted to provide against the coiling of said table-forming member and accordingly effecting the retention of said 15 table-forming member in horizontal position.
3. In a device of the character described, the combination with a car having facing seats, of a casing mounted upon the wall of the car between said seats, a spring-actuated 20 roller, a flexible table wound upon said roller, a rigid strip carried by the outer end of the table and a card receptacle carried by said strip.
4. In a device of the character described, 25 the combination with a car having facing seats, of a casing mounted upon the wall of

the car between said seats, a spring-actuated roller, a flexible table wound upon said roller, a rigid strip carried by the outer end of the table, a card receptacle carried by said strip, and a shell within said casing into which said card receptacle is adapted to fit when the table is wound upon said roller. 30

5. In a device of the character described, the combination of a car having facing seats, 35 a casing mounted upon the wall of the car between said seats, a spring-actuated roller within said casing, a flexible table adapted to be wound upon said roller, a card receptacle carried by and moving with said 40 table, inter-engaging means between said table and the arms of the seats, an oscillatory shaft, fingers carried by said shaft and arranged to engage the table to prevent the withdrawal of the same and manually oper- 45 able means for actuating said shaft.

In testimony whereof I affix my signature, in the presence of two witnesses.

JOHN EDWARD NEALY.
